ELASTIC SPAT.

Filed June 25, 1930

UNITED STATES PATENT OFFICE

LEO WIESENFELD, OF BROOKLYN, NEW YORK

ELASTIC SPAT

Application filed June 25, 1930. Serial No. 463,603.

This invention relates to a new and useful improvement in a spat.

The invention has for an object the provision of a device of the class mentioned which is of simple durable construction, dependable in use and efficient in action, and which can be manufactured and sold at a reasonable cost.

The invention proposes in combination 10 with a spat having a side opening of a strip of material attached along one edge of said opening, stitches between said strip and spat forming spaced horizontal pockets with openings at said edge, elastic tabs secured at 15 their inner ends within said pockets, snap fastener elements on the free ends of said tabs, and complementary snap fastener elements on the other edge of said spat opening.

The invention also proposes a means for 20 detachably holding said strip in place. Another object of the invention is to provide a means for changing the position of said complementary snap fastener elements for adjustments of the tensions of said tabs in 25 closed positions.

For further comprehension of the invention, and of the objects and advantages thereof, reference will be had to the following description and accompanying drawing, and 30 to the appended claims in which the various novel features of the invention are more particularly set forth.

In the accompanying drawing forming a material part of this disclosure:—

35 Fig. 1 is a side elevational view of a spat constructed according to this invention.

Fig. 2 is a plan view of Fig. 1.

Fig. 3 is a fragmentary enlarged sectional view taken on the line 3—3 of Fig. 1.

40 Fig. 4 is a fragmentary enlarged inside elevational view.

Fig. 5 is a fragmentary inside elevational view of a portion of the spat.

45 Fig. 6 is a view similar to Fig. 5, but illustrating a modified form.

Fig. 7 is a sectional view taken on the line 7—7 of Fig. 6.

Fig. 8 is an elevational view of a portion of the inside of the spat constructed according to modified form.

Fig. 9 is an enlarged sectional view taken on the line 9—9 of Fig. 8.

Fig. 10 is a similar view to Fig. 1 showing a modified form of the invention.

Fig. 11 is an enlarged detailed fragmentary view of a portion of Fig. 6.

The spat 10 has a side opening 11 and a strip of material 12 is attached along one edge of said opening. The attachment of strip 12 is accomplished by stitches 13 and 14. The stitches 13 extend up and down and serve to hold the rear edge of the strip 12 in place, while the stitches 14 extend longitudinally and in addition to holding the strip in place from a plurality of horizontal spaced 65 pockets 15. Elastic tabs 16 have their inner ends 17 secured within the pockets and extend through the pockets so that their outer ends slightly project. Snap fastener elements 18 are attached upon the free ends of 70 the tabs 16 and are engageable on complementary snap fastener elements 19 attached upon the other edge of the spat opening.

The spat 10 is made from heavy felt. It 75 consists of two side sections 20 and 21 attached together along the front and rear edges 22 and 23 respectively. The attachment is accomplished by sewing the adjacent edges of the sections together by stitches 24, then securing a binding strip 25 over the edges 80 forming a finished job. The binding strips should preferably be of leather. The section 20 is formed of two portions indicated by reference numerals 26 and 27 and the adjacent edges of these portions constitute the side 85 opening 11 of the spat.

The spat 10 is also shown finished by top and bottom binding strips 28 and 29 respectively secured along the top and bottom inner edges. The securing is accomplished by 90 stitches. A triangular heel piece 30 is attached at the rear portion of the spat at the lower edge. A base elastic strap 31 is attached across the side sections 20 and 21 for engaging under the shoe of a wearer. The side opening 11 of the spat extends from the top completely to the bottom. The snap fastener elements 18 are socket elements and the other elements 19 are stud elements. The 95 socket elements are immediately adjacent the 100

edge of the portion 26, while the stud elements 19 are spaced slightly inwards from the edge of the section 27. This arrangement allows an overlapping of the edges as clearly shown in Fig. 2. A reinforcement strip 32 is secured by stitches 33 to the inner side of the portion 27 and the snap fastener studs 19 engage through this strip and through the material of the spat so as to be mounted upon a firm 10 foundation.

In the modified form of the device illustrated in Figs. 6 and 7, a means has been shown for detachably holding the strip 12^a in place. This strip 12^a is formed of two layers 15 indicated by reference numerals 34 and 35. Stitches 14 secure these layers together and form the horizontal pockets 15 before referred to. A row of hookless fastener elements 36 are attached upon the rear edge of the strip 12^a and are engageable with a complementary row of hookless fastening elements 37 secured upon a strip 38 attached on the spat. The row of hookless fastener elements 36 are attached on the strip 12^a only 20 up to a point a short distance from the end, and that point is indicated by the numeral 50. Thereafter the strip 38 is extended and the elements 37 are attached thereon. A control slide 39 is arranged on these hookless elements 30 for latching them together when moved in one direction, and releasing them when moved in the other. A stop 40 is arranged on one end of the strip 38 to prevent complete disengagement of the control slide 39, but 35 when the slide is pulled completely off the opposite end of the strip 38 the strip 12^a is released and may be removed. To replace the strip, care must be taken to see that the first few hookless fastener elements on each side 40 are pushed through the slide 39 after which the elements which have been passed through the slide 39 may be grasped and the remaining elements latched together by continuing the movement of the slide. As a result, the 45 strip 12^a can be replaced by a new one when the snap fasteners 18 become weak. Furthermore, if a different style snap fastener is desired, the change can be effected very easily and quickly.

50 Snap fastener elements 19 may be secured to resilient tabs 16' as shown in Fig. 10.

In the modified form of the device illustrated in Figs. 8 and 9, a means has been shown for changing the position of the complementary snap fastener studs 19 for adjustments of the tension of the tabs 15 when the tabs are closed. This means comprises top and bottom clips 41 attached upon the top and bottom edges of the spat. These clips are 55 formed with elongated slots 42 slidably receiving eyelets 43 mounted upon the ends of a strip 44. A plurality of intermediate U shaped clips 45 are mounted between the clips 41 and are formed with U shaped slots 46. 60 The snap fastener studs 19 are firmly attached 65

upon the strip 44 and extend through the U shaped slots 46. A piece of elastic material 47 is interposed between the ends of the strip 44 and normally in contracted position holds the studs 19 in one of the ends of the U shaped slots 46.

70 For changing the positions of the studs 19, it is merely necessary to move the strip 44 so as to stretch the insert 47 for moving the studs 19 out from the ends of the U shaped slots and then move the strip 44 laterally as allowed by the slots 42 to a new position so that when released the elastic insert 47 contracts the strip and moves the snap fastener studs into the other ends of the U shaped slots 44. In the new position the studs 19 are located at different distances from the edge forming the side opening in the spat and necessarily at a different distance from the snap fastener sockets.

75 In operation of the spat, it is engaged upon a shoe in a conventional fashion, that is, the strap 31 is positioned below one shoe and the spat around the shoe. The snap fastener studs and sockets are engaged to close the side opening of the spat. The elastic tabs 15 are depended upon to automatically adjust themselves so as to snugly hold the spat upon one's foot irrespective of the size 80 of the foot.

85 While I have shown and described the preferred embodiment of my invention, it is to be understood that I do not limit myself to the precise construction herein disclosed and the right is reserved to all changes and modifications coming within the scope of the invention as defined in the appended claims.

90 Having thus described my invention, what I claim is new, and desire to secure by United States Letters Patent is:

105 1. The combination with a spat having a side opening of a strip of material attached along one edge of said opening, stitches between said strip and spat forming spaced horizontal pockets with openings at said edge, elastic tabs secured at their inner ends within said pockets, snap fastener elements on the free ends of said tabs, complementary snap fastener elements on the other edge of said spat opening, and means for changing the position of said complementary snap fastener elements for adjustments of the tensions of said tabs in closed positions.

110 2. The combination with a spat having a side opening of a strip of material attached along one edge of said opening, stitches between said strip and spat forming spaced horizontal pockets with openings at said edge, elastic tabs secured at their inner ends within said pockets, snap fastener elements on the free ends of said tabs, complementary snap fastener elements on the other edge of said spat opening, and means for changing the position of said complementary snap fastener elements for adjustments of the ten- 115

- sions of said tabs in closed positions, comprising a strip supporting said snap fastener studs and longitudinally slidably mounted upon said spat, a resilient insert in said strip, and a plurality of clips in the spat and formed with U shaped slots receiving said studs, and said resilient insert being capable of holding the studs in one of the ends or the other of the ends of said U shaped slots.
- 5 3. The combination with a spat having a side opening of a strip of material attached along one edge of said opening, stitches between said strip and spat forming spaced horizontal pockets with openings at said edge, elastic tabs secured at their inner ends within said pockets, snap fastener elements on the free ends of said tabs, complementary snap fastener elements on the other edge of said spat opening, and means for changing
- 10 the position of said complementary snap fastener elements for adjustments of the tensions of said tabs in closed positions, comprising a strip supporting said snap fastener studs and longitudinally slidably mount-
- 15 ed upon said spat, a resilient insert in said strip, and a plurality of clips in the spat and formed with U shaped slots receiving said studs, said resilient insert being capable of holding the studs in one of the ends or the other of the ends of said U shaped slots, and said longitudinally slidably mount-
- 20 ing of said strip comprises clips attached upon the spat and having elongated slots and eyelets fixed upon the ends of the strip
- 25 and engaging said slots.
4. The combination with a spat having a side opening of a strip of material attached along one edge of said opening, stitches between said strip and spat forming spaced
- 30 horizontal pockets with openings at said edge, elastic tabs secured at their inner ends within said pockets, snap fastener elements on the free ends of said tabs, complementary snap fastener elements on the other edge of
- 35 said spat opening, and means for changing the position of said complementary snap fastener elements for adjustments of the tensions of said tabs in closed positions, comprising a strip supporting said snap fastener studs and longitudinally slidably mount-
- 40 ed upon said spat, a plurality of clips in the spat and formed with U shaped slots receiving said studs, and means for holding the
- 45 studs in one or the other of the ends of said
- 50 U shaped slots.

In testimony whereof I have affixed my signature.

LEO WIESENFELD.
